UNITED STATES PATENT OFFICE.

SIDNEY O. MARTIN, OF ST. LOUIS, MISSOURI.

DESIGN FOR A SIGNAL.

Application filed October 11, 1922. Serial No. 3,934. Term of patent 14 years.

To all whom it may concern:

Be it known that I, SIDNEY O. MARTIN, a citizen of the United States, residing at St. Louis, in the State of Missouri, have invented a new, original, and ornamental Design for Signals, of which the following is a specification, reference being had to the accompanying drawing, forming part thereof, and in which—

Figure 1 is a front elevation of the novel design of signal;

Figure 2 is a similar view wherein the translucent lenses of the signal are removed; and

Figure 3 is a side elevation of the novel design of signal.

I claim:

The ornamental design for a signal, as shown.

SIDNEY O. MARTIN.
